LOOPER-OPERATING MECHANISM FOR SEWING MACHINES

Application filed January 28, 1926. Serial No. 84,402.

The invention relates to new and useful improvements in looper operating mechanisms for sewing machines, and more particularly to a mechanism which gives to the looper a variable movement.

An object of the invention is to provide a looper operating mechanism which is so constructed that the thread carrying looper is moved forward into the loop of the needle thread more rapidly than it is retracted therefrom.

A further object of the invention is to provide a looper operating mechanism of the above type wherein the looper is positively moved by connected cranks and links.

A still further object of the invention is to provide a machine having a needle which is moved upwardly much more rapidly than it is downwardly, with a thread carrying looper operating mechanism which is adapted to move the thread carrying looper more quickly into the thread carrying loop than it is retracted therefrom.

These and other objects will in part be obvious and will in part be hereinafter more fully described.

In the drawings which show by way of illustration one embodiment of the invention—

Figure 1 is a view partly in side elevation and partly in section showing a machine embodying my improved looper operating mechanism;

Fig. 2 is a sectional view through the needle head of the machine and showing the mechanism connected to the needle bar for operating the same;

Fig. 3 is a view partly in section and partly in side elevation showing the essential parts of the looper operating mechanism and the needle with the looper at the forward end of its stroke, and

Fig. 4 is a view similar to Fig. 3, but showing the looper at the rear end of its stroke and the needle at the lower end of its stroke.

The invention is directed broadly to a sewing machine having a reciprocating needle bar carrying a needle, which needle bar is operated by devices constructed and arranged so as to move the needle bar more

quickly on its upward stroke than on its downward stroke. This enables the needle to be quickly retracted from the goods being stitched and give ample time for the feeding of the material. Associated with this variably timed operating mechanism for the needle is a variable looper moving mechanism. The looper is of the thread carrying type and moves into and out of the needle thread loop, and also laterally to avoid the needle as is usual in this type of machine. The looper is moved into the needle thread loop very quickly and is retracted from the loop much more slowly. This enables the looper to get into the needle thread loop although the needle moves to the upper end of its stroke very quickly. The looper is moved by means of a crank in the main shaft to which a link is connected. This link in turn is connected to a lever. The lever is in turn pivoted to a link which is connected at its lower end to a crank on the shaft which rigidly supports the looper. The lever is pivoted at one side of a line connecting the centers of the main shaft and the looper shaft, and as a result, the links and lever take such position that the stroke of the looper on its forward movement is accomplished while the crank on the main shaft is moving through an arc of less than one hundred and eighty degrees, while the stroke of the looper on its return movement is accomplished while the crank on the main shaft is moving through an arc of considerably greater than one hundred and eighty degrees.

Referring more in detail to the drawings, my improved invention is shown applied to a machine of the type disclosed in detail in the application of Christensen & LeVesconte, Serial No. 9,584, filed February 16, 1925.

The machine consists of a supporting standard 1 which is provided with an overhanging upper end 2 on which a horizontal housing 3 is mounted. This housing 3 is provided with a laterally projecting portion or auxiliary housing 4 in which a needle bar 5 is mounted and reciprocates. The housing 3 also carries a depending arm 6. Extending laterally from the lower end of said depending arm 6 is a work supporting arm 7.

- Mounted in this work supporting arm 7 is a looper shaft 8 on which is mounted a thread carrying looper 9. The thread carrying looper 9 is rigidly attached to the shaft. As shown in Figures 1 and 2, there are two loopers, for the reason that the needle bar 5 carries two needles 10 and 11. It is understood that the loopers cooperate with the respective needles and instead of two loopers, only one looper may be used, or even more than two loopers may be used.
- The needle bar is reciprocated by means of a lever 12 which is pivoted at 13 in the auxiliary housing 4. This lever is connected by means of a link 14 to the needle bar 5. The lever 12 at its rear end is connected to a link 15, and the link 15 is in turn connected to a crank 16 formed in a shaft 17. This shaft 17 is the main shaft of the machine. The link 15 is connected at 18 to the lever 12, and this pivotal connection 18 and the pivot of the lever 12 are so disposed relative to the shaft that the needle is moved to the lower end of its stroke while the crank 16 is turning through an arc considerably greater than one hundred and eighty degrees. The needle bar is raised to the upper end of its stroke while this crank is passing through an arc of considerably less than one hundred and eighty degrees. Thus it is that the needle is caused to move quickly on its upstroke and be withdrawn from the fabric at an early period in the stitch cycle so as to permit the material to be moved by the feed of the machine. This needle operating mechanism per se forms no part of the present invention, but is shown, described and claimed in the application of Christensen & LeVesconte above referred to.
- The material is held on the work support by a presser foot 19 carried by a presser bar 20. It is fed off the end of the work supporting arm by a feed dog 21 carried by a feed bar 22. This feeding mechanism forms no part of the present invention and may be of the usual character.
- The looper supporting shaft 8 is moved endwise by means of a lever 23 which is connected by a link 24 to a sleeve 25 mounted on the looper shaft between fixed collars 26, 26. The sleeve is free on the shaft so that the shaft may oscillate in the sleeve. The oscillations of the lever 23, however, will move the looper shaft endwise, and thus give to the looper a needle avoiding movement. The lever 23 is oscillated by means of an eccentric strap 27 which cooperates with an eccentric 28 on the main shaft 17. Fixed to the eccentric 28 is a crank pin 29. This crank pin is connected to a link 30. The link 30 is connected at 31 to an elbow lever 32. The elbow lever 32 is secured to a short shaft 33 mounted in bearings in the frame of the machine. This shaft 33 merely permits the lever to swing freely through the

movements of the link 30 connected therewith. A link 34 is pivotally connected at 35 to the elbow lever 32. This pivotal connection 35 is located at the elbow in the lever. The link 34 is in turn connected to a crank 36 on the end of the looper supporting shaft 8.

When the parts are in the position shown in Fig. 3, the looper is at the forward end of its stroke, while when the parts are in the position shown in Fig. 4, the looper is at the rear end of its stroke. The main shaft is turning in a counter clockwise direction as viewed in these figures of the drawings. It will be apparent, therefore, that when the crank 29 moves from the broken line $x-x$ in Fig. 3, around to the broken line $y-y$ of this figure, and also Fig. 4, said crank will have moved through an arc indicated by the line b which is considerably greater than one hundred and eighty degrees. During this movement of the crank, the looper is retracted. When the crank moves from the broken line $y-y$ of Fig. 4, to the broken line $x-x$ of this figure, it moves through an arc indicated by the line a , which is considerably less than one hundred and eighty degrees. During this movement of the crank, the looper receives its entire forward movement.

From the above it will be apparent that the looper has a very quick forward movement, and a relatively slow retracting movement. These movements of the looper are timed to correspond to the variable movements of the needle. In other words, during a portion of the stitch cycle, which is considerably less than one-half of a stitch cycle, the needle moves from its lowest to its extreme highest position, and the looper moves from its rear to its extreme forward position, and will, therefore, enter the needle thread loop with certainty. This enables the needle to clear the material at an early period in the stitch cycle and gives a much greater time for the feed to take place before the needle again penetrates the material.

The machine is designed particularly for rapid stitching of tubular articles such as sleeves, leg portions and the like, of garments, and particularly to the stitching of these tubular articles one after the other, the articles being formed around a work supporting arm and stitched as they are fed off from the arm. One article is stitched right after the other without stopping the machine, and the machine is driven at an exceedingly high speed. In order to render the machine efficient under these conditions, the variable operating mechanism for the needle and looper has been devised. This mechanism insures proper stitch formation under the conditions stated.

It is obvious that minor changes in the details of construction and arrangement of the parts may be made without departing

from the spirit of the invention as set forth in the appended claims.

Having thus described the invention, what I claim as new and desire to secure by Letters-Patent, is—

5. 1. A looper operating mechanism for sewing machines comprising a looper supporting shaft, a thread carrying looper rigidly secured to said shaft, an actuating shaft for said looper supporting shaft, a crank on said actuating shaft, a crank on said looper supporting shaft, a lever pivotally supported at one side of a line joining the centers of said shafts and having its pivotal axis substantially parallel with the axis of the actuating shaft, a link pivoted to the crank on the actuating shaft and to said lever, and a second link pivoted to the lever and to said crank on the looper shaft, said pivotal connections between the links and the lever being so disposed that the looper operating shaft is oscillated through its entire throw while the actuating shaft is moving through an arc of considerably less than one hundred and eighty degrees.

2. A looper operating mechanism for sewing machines comprising a looper supporting shaft, a thread carrying looper mounted thereon, said looper supporting shaft having a crank, an actuating shaft for the looper supporting shaft, a crank carried by said actuating shaft, an elbow lever pivoted to turn about a center at one side of a line joining the centers of said shafts, a link connecting the crank on the actuating shaft with the end of said elbow lever, a link connected to said lever at the elbow thereof and to the crank on the looper supporting shaft.

3. A looper operating mechanism for sewing machines comprising a looper supporting shaft, a thread carrying looper rigidly mounted thereon, said looper supporting shaft having a crank on the end thereof, an actuating shaft located above the looper supporting shaft and having a crank on the end thereof, an elbow lever pivoted at one side of a line joining the center of the shafts, a link connected to said crank on the end of the actuating shaft and to the end of said elbow lever, a second link connected to the lever at the elbow thereof, and to the crank on the end of the looper supporting shaft.

4. The combination of a reciprocating needle bar carrying a needle, a main actuating shaft having a crank formed therein, a lever connected to the needle bar and having a link connection with the actuating shaft disposed so that said needle is moved from its lowest to its extreme upper position, while the main actuating shaft is rotating through an arc considerably less than one hundred and eighty degrees, a looper supporting shaft, a thread carrying looper carried thereby and cooperating with said needle, devices operated by said main actuating shaft for oscillating

said looper supporting shaft, said devices including means whereby said looper is moved from the rear end of its stroke to the forward end of its stroke while the needle is moving on its up stroke.

5. The combination of a reciprocating needle bar carrying a needle, a main actuating shaft having a crank formed therein, a lever connected to the needle bar and having a link connection with the actuating shaft disposed so that said needle is moved from its lowest to its extreme upper position, while the main actuating shaft is rotating through an arc considerably less than one hundred and eighty degrees, a looper supporting shaft, a thread carrying looper carried thereby and cooperating with said needle, said looper supporting shaft having a crank, said main shaft having a crank, a lever pivotally supported at a point at one side of a line passing through the centers of said shafts, a link connecting the crank on the main actuating shaft with said lever, and a link connecting said lever with the crank on the looper supporting shaft, said links being so disposed that said looper supporting shaft is oscillated so as to move said looper from the rear end of its stroke to the forward end of its stroke while the needle is on its up stroke.

6. In a sewing machine, the combination of a rotating shaft, a reciprocating needle, needle actuating devices connected with said shaft for imparting reciprocations to said needle, said devices being so disposed that less than half of a revolution of said shaft will be required to move the needle from one extreme position to the other and more than half a revolution of said shaft will be required to move the needle on its return movement to the first named extreme position, a looper cooperating with said needle and devices for actuating said looper connected with said rotating shaft, said looper actuating device being so disposed and arranged as to cause the looper to reach its extreme positions at the same time as the needle.

7. The combination of an actuating shaft, a reciprocating needle bar carrying a needle, means operated by said shaft for reciprocating said needle bar and moving the needle bar more quickly on its upward stroke than on its downward stroke, a looper support, a looper rigidly secured to said support, means for moving said looper forward and backward including links and levers for connecting said looper support to said actuating shaft, said links and levers being constructed and arranged so as to move the looper throughout its entire forward stroke while the needle is on its upstroke, and for moving said looper throughout its entire retracting stroke, while the needle is on its down stroke.

In testimony whereof, I affix my signature.
